VIBRATING NEEDLE CHAIN STITCH
MECHANISM

Frank L. Jennings, Philadelphia, Pa.

Application February 7, 1936, Serial No. 62,753

6 Claims. (Cl. 112—201)

The object of the invention is to provide improvements in button sewing machines, but more especially in the relatively automatic operation of the looper and thread finger.

5 Another object is to provide in such a device the combination of a rotatable looper, in combination with a diagonally reciprocatory thread finger.

A further object is to provide an improved 10 thread finger, which is formed of a single elongated member, provided at its relatively free end with a reversely, angularly directed, relatively slender, integral, pointed extension, which operates to remove a loop laterally from the above- 15 mentioned looper, and temporarily hold such loop to one side until another loop has been produced, and duly inserted thru said first loop.

Still another object is to provide, in combination with the foregoing, means to guide the relatively free end portion of said finger in a diagonally extending path, while the opposite or actuated end portion of said finger element is restrained to a rectilinear path, which is angularly disposed with respect to said first path.

25 With these and other objects in mind, the invention comprises further details of construction and operation, which are hereinafter fully brought out in the following description, when read in conjunction with the accompanying 30 drawing, in which Fig. 1 is a fragmentary top plan view of a portion of a button sewing machine, showing one embodiment of the invention; Fig. 2 is a vertical longitudinal section on the line 2—2 of Fig. 1; Fig. 3 is a vertical transverse 35 section on the line 3—3 of Fig. 1; and Fig. 4 is plan view of a portion of the mechanism shown in Fig. 1, but with the thread finger at the opposite end of its normal path of movement.

Referring to the drawing, only a portion of a 40 button sewing machine is represented, as being sufficient to illustrate the construction and operation of the present invention in one of its embodiments.

In this construction, a rotatable shaft 1, is 45 shown as being provided with a pinion 2 for connecting said shaft to any suitable form of driving or operating mechanism. Said shaft is also provided with a cam 3, and upon its free end with a looper 4, of any well-known or suitable 50 shape.

Substantially parallel with said shaft is an oscillatory bar 5, pivotally fixed at 6, and separated from, as well as being operated by, said cam through the medium of a suitable shoe 7. To the 55 free end portion of said bar is pivotally connected

at 8, an auxiliary extension 9, the angular relation of which extension to said bar being adjustably fixed by means of a suitable set screw 10, while said extension is, itself, pivotally connected at 11 to a block 12, which, in turn, is reciprocably mounted within the usual guides 13. 5

To that end portion of said block adjacent to the looper 4, there is pivotally connected at 14 a preferably angularly shaped link 15, which extends forwardly and diagonally to one side of 10 said looper, and is provided upon its free forward-most end portion with a slender, integral, reversely directed, finger portion 16.

The forward end portion of said link is also provided with a depending pin 17, which moves 15 to and fro in a fixed slot 18, thereby guiding the free end portion of said link, and particularly the thread finger 16, in a diagonal path with respect to the plane of rotation of the looper 4. 20

In the operation of this device, the bar 5 is 25 normally maintained in slidable bearing engagement against the cam 3, which latter, upon being rotated, shifts the thread finger 16 from the position shown in Fig. 1, to the position shown in 30 Fig. 4, and vice versa, as the looper 4 rotates in its customary manner, said bar 5 being at all times maintained in cooperation with the cam 3, through the medium of the tension spring 19. 35

In the present invention, one of the principal 40 features resides in the fact that the slot 18, which guides the thread finger alternately to and fro, is diagonally disposed with respect to the plane of movement of the looper. The advantage of this construction resides in the fact that 45 a loop of thread, which has been previously formed by said looper, is easily and very quickly removed diagonally from the path of movement of said looper, and temporarily held in such position until the looper has had an opportunity to 50 form a second, or succeeding, thread loop, whereupon the thread finger instantly releases the first loop.

In previous constructions, wherein the thread 55 loop is removed from the looper in line with the path of movement of said looper, or at least parallel therewith, the thread loop remains in contact with the thread finger for an appreciably longer period, and is thereafter released only as a result of the finger forcibly pushing the strands out of the way. By contrast, in the improved construction, the removal of the thread from the finger is materially assisted by the diagonal retraction of the finger itself, wherefore it is self evident that even such an improvement with 55

relation to the additional fraction of a second, gained at this stage of the stitch formation, results in a greatly magnified improvement in the final results obtained.

- 5 It is to be understood, that this invention is not limited to the exact shape, arrangement, and angular direction of the path of movement of the thread finger, but said invention, instead, is to be considered as covering all variations of such 10 construction and operation as may fall within the appended claims.

Having thus described my invention, what I claim and desire to protect by Letters Patent of the United States is:—

- 15 1. In a button sewing machine, the combination of a rotary thread looper, a link provided with an integral finger operative to draw a thread loop from and momentarily to one side of the path of movement of said looper, means to reciprocate one end of said link in substantial alignment with the plane of movement of said looper, and means to guide the finger portion of said link in a path angularly disposed with respect to the plane of rotation of said looper.
- 20 2. In a button sewing machine, the combination of a rotary thread looper, a shaft carrying said looper, a cam also carried by said shaft, a link having a finger-like extension, means cooperating with said cam to reciprocate said link, and guiding means to maintain the path of movement of said finger extension diagonally with respect to the plane of movement of said looper.
- 25 3. In a button sewing machine, the combination of a rotary thread looper, a shaft carrying said looper, a cam also carried by said shaft, a link having a finger-like extension, a block movable in a fixed path and pivotally attached to one end portion of said link, means to guide 30 another portion of said link diagonally with respect to the line of movement of said looper, and
- 35 40

a connecting bar pivotally mounted and engaging said cam and pivotally attached to said block.

4. In a button sewing machine, the combination of a rotary thread looper, a shaft carrying said looper, a cam also carried by said shaft, a link having a finger-like extension, a block movable in a fixed path and pivotally attached to one end portion of said link, means to guide another portion of said link diagonally with respect to the plane of movement of said looper, 10 a connecting bar pivotally mounted and engaging said cam and pivotally attached to said block, and means to adjust the relation of said block to said bar.

5. In a button sewing machine, the combination of a rotary thread looper, a shaft carrying said looper, a cam also carried by said shaft, a link having a finger-like extension, a block movable in a fixed path and pivotally attached to one end portion of said link, means to guide another portion of said link diagonally with respect to the line of movement of said looper, a connecting bar pivotally mounted and engaging said cam and pivotally attached to said block, and resilient means to yieldingly maintain said bar in cooperation with said cam.

6. In a button sewing machine, the combination of a rotary thread looper a shaft carrying said looper, a cam also carried by said shaft, a link having a finger-like extension, a block movable in a fixed path and pivotally attached to one end portion of said link, means to guide another portion of said link diagonally with respect to the line of movement of said looper, a connecting bar pivotally mounted and engaging said cam 35 and pivotally attached to said block, means to adjust the relation of said block to said bar, and resilient means to yieldingly maintain said bar in cooperation with said cam.
